GRINDING MILL

Application filed October 24, 1929. Serial No. 402,254.

This invention relates to grinding mills, it more particularly relating to that type of grinding mill known as a hammer mill in which a series of pivoted rotary hammers ⁵ 55 contact with a stationary surface to pulverize the material; the invention especially relating to the construction of the hammers.

In hammer mills it is usual to employ hammers, the ends of which are stepped to form ¹⁰ 60 a plurality of cutting teeth. The object of my invention is to so arrange the teeth as to provide for a more effective pulverizing action upon the material.

In the accompanying drawings:

¹⁵ Fig. 1 is a partial, vertical cross-sectional view of so much of a hammer mill as is needed to illustrate my improvements.

Fig. 2 is a fragmentary end view of my improved hammer together with some of the ²⁰ 65 associated parts.

Fig. 3 is a reduced scale partial cross-sectional view of a typical hammer mill.

Referring to the drawings, in Fig. 3 there is shown a mill in which my improved hammers have been incorporated, 1 and 2 representing the upper and lower casing members connected together in any suitable manner. The lower casing member carries in suitable bearings (not shown) a revolvable shaft 3 ²⁵ 70 upon which is secured a plurality of flat circular disks 4 having a series of openings 5 equally spaced and concentrically disposed and through which are inserted rods 6 to form the pivots for the hammers 7.

²⁵ Each hammer 7 is formed of a metallic bar of hard tough steel rectangular in cross-section. These hammers are of reversible character and an opening 8 is provided near each end to receive a rod 6 after the hammer ⁴⁰ 75 has been placed between a pair of disks 4, thus providing a secure, loose, pivotal mounting. On rotation of the shaft the hammers fly outwardly by the action of centrifugal force and cooperate with a curved breaker ⁴⁵ 80 plate 10 secured within the upper housing 1; the radius of curvature of the plate being larger than that of the path of the extremities of the hammer and being so placed that the inner curved surface converges with the ⁵⁰ 85 path of the revolving hammer but spaced

therefrom at the point of nearest approach as indicated at 11 in Fig. 1.

The material to be ground is sometimes sufficiently small as to be able to pass through the space 11, but when fed into the mill in a ⁵⁵ 60 manner which causes the material to flow in a line tangential of the path of the revolving hammers, it is thrown with great force towards the curved breaker plate, from which it rebounds towards the hammers, this being repeated until the material passes through the space 11 and falls on the perforated screen ⁶⁵ 70 10', those particles which will not pass through the screen perforations being returned for further breaking.

In the action of the hammers upon the material, the material is pulverized to better advantage and with less power requirements when the corners on the advancing sides of the hammers are new and comparatively ⁷⁵ 80 sharp and attempts have been made to increase the volume of ground material produced by forming the hammers with stepped ends to provide a plurality of cutting edges at different distances from the pivoted axis ⁸⁵ 90 of the hammer, and also providing the end of the hammer with a plurality of spaced teeth to provide a plurality of cutting edges each of which is the same distance from the pivoted axis of the hammer. In the first instance, due to the fact that there are no spaces or notches between the cutting edges, the opportunity for rebound of the material is not present, while in the second instance, the fact that the cutting edges are all the same distance from the pivoted axis of the hammer results in ineffective action of all but the advanced cutting edge.

In carrying out my invention I have so disposed the cutting edges on the end of the hammer that each cutting edge will be effective for the cutting or pulverizing of the material by placing the cutting edges at varying distances from the pivotal axis of the hammer and also place between each cutting edge a recess or notch to enhance the opportunity for rebound of the material. Referring to Fig. 1 it will be noticed that the end of the hammer 7 has a central tooth 12 and on each side thereof a tooth 14, adjacent teeth ⁹⁵ 100

being separated by a pronounced recess or notch 13. It will also be noticed that the intermediate tooth 12 is longer than the other teeth 14 so that the cutting edge thereof will 5 be at a greater distance from the pivotal axis of the hammer. At the side edges of the hammer additional notches 15 are provided to form additional cutting edges 15' which are of a less distance from the pivotal center 10 than the cutting edges of the teeth 14. From this construction it will be seen that the cutting edges being of varying distances from the axis of the hammer which increase progressively reversely to the direction of rotation of the hammer, indicated by the arrow in Fig. 1, a more effective pulverizing action is had upon the material; and, further, due to the notches or recesses between the teeth, 15 opportunity for rebound of the material is enhanced in heavy feeding, since small portions 20 of the material expand into the notches after contact with the hammer.

These hammers are reversible both end to end and side by side to increase the life of the 25 hammer and for that purpose each end and each side thereof is constructed the same.

Having thus described my invention, I claim:

In a grinding mill, a rotary pivoted hammer, the free ends of said hammer having a 30 central tooth and other teeth on each side of said central tooth with notches between said teeth, said central tooth being of greater length than said other teeth, the sides of said 35 hammer adjacent the other teeth being notched to form additional cutting edges, said additional cutting edges being at a lesser distance from the pivotal axis of said hammer than the cutting edges formed on the other 40 teeth and the cutting edges on said central tooth being at a greater distance from the pivotal axis of said hammer than the cutting edges on the adjacent tooth, the notches between the teeth extending throughout the 45 width thereof and being of uniform width.

In testimony whereof I have hereunto set my hand this 22nd day of October, 1929.

RICHARD S. IGLEHART.
